UNITED STATES PATENT OFFICE

LEOPOLD G. STANLEY, OF MAPLEWOOD, NEW JERSEY, ASSIGNOR TO STANLEY & STANLEY, INCORPORATED, OF NEW YORK, N. Y., A CORPORATION OF NEW YORK

COMBINATION CASE

Application filed June 20, 1927. Serial No. 200,178.

This invention is a novel combination case, especially for pocket use and has reference more particularly to a foldable case made from leather or similar sheet material adapted for a certain combination of uses as will be herein described.

The general object of the invention is to afford a pocket case adapted to the uses below set forth and which will be compact when folded, convenient in use, simple and durable. A particular object is to provide a leather or other case adapted to contain paper money or the like, keys and other objects. Further objects and advantages will be explained in the hereinafter following description of an illustrative embodiment of the invention or will be apparent to those conversant with the subject. To the attainment of such objects and advantages the present invention consists in the novel combination case and the novel features of construction, arrangement, combination and detail herein illustrated or described.

In the accompanying drawings Fig. 1 is what may be described as an inside view of a combination case embodying the present invention, with the parts somewhat opened up to show better the construction and partly broken away to show the interior.

Fig. 2 is a similar view of the other or outer side of the article.

Figs. 3 and 4 are perspective views respectively of the two sides of the article in closed condition.

Fig. 5 is a side view of a detached element.

The body of the combination case of this invention is shown constructed of two main layers or pieces 6 and 7 of leather or similar material, the layer 6 being what is here termed the interior and the layer 7 the exterior portion, as these layers take these respective positions when the article is closed. The main pieces 6 and 7 are attached by stitching 8 around the lower side and the two ends, but left unstitched at the top thus leaving an opening and space 9 constituting the main or long pocket adapted to receive paper money or the like.

The combined main pieces 6 and 7 may be considered as comprising three sections,

namely a center section 10, an inner end section 11 and an outer end section 12. In closing the article the section 11 is turned in upon the central section and the outer section 12 upon them, and the parts are preferably secured in this position, for example by a fastener member 13 on the section 11 and a complementary fastener member 14 on the section 12, these being for example of the ball and socket snap fastener type.

For greater security for the main or long pocket 9 there is shown a closing flap 15 which is connected by stitching 16 to the inner leather layer 6, this flap reaching over the top of the pocket and down at the exterior.

The space between the central section 10 of the article and the infolded end sections 11 and 12 constitutes a space which is open at the top and bottom, but is available for containing attached objects such as keys. For this purpose there are shown a number of snaffles or hooks 17 attached to the upper part of the central section 10 of the inner main layer 6. Preferably these are attached at that portion of the layer 6 which is reinforced by the attached portion of the leather flap 15, as shown, thus giving a very strong and effective arrangement. Upon certain of the key hooks or loops 17 are shown a number of keys 18 which are seen to be snugly accommodated in this central interior space.

At the opposite or outer side of the central section 10, and attached to the outer leather layer 7, there may be arranged a small flat pocket 19 for the reception of business cards or the like, this pocket being shown attached by stitching 20 to the center of the layer 7. The closing flap 15 may be arranged to close not only the main or long pocket 9 containing paper money, etc., but also the small or card pocket 19. For this purpose a fastener member 21 is shown on the pocket 19 adapted to be engaged by a complementary fastener member 22 on the free end of the flap 15. Figs. 1 and 2 show these several parts in their open condition and Figs. 3 and 4 show them in their closed condition.

The long layers 6 and 7 as attached, with the side open, may be considered as an elongated

gated bill-fold pocket, to receive paper money or the like, and foldable as a whole in any manner to enclose a key receiving space, in which are accommodated keys or the like and the described snaffles or other holding means, permanently attached to the interior of one section, preferably the middle one. The article as a whole performs a combination of services in a very handy manner and is simple, rugged, convenient and compact.

The swivelled key holding devices 17 are shown securely attached by their rings to the case in a manner claimed to be novel, these rings extending through short slits in layer 6 and therebehind being anchored by a leather strip threaded through all the rings and having its widened ends stitched firmly in place.

It will thus be seen that there has been described a novel combination case for pocket use embodying the principles and attaining the objects of the present invention. Since various matters of construction, arrangement, combination and detail may be modified without departing from the principles it is not intended to limit the invention to such matters except so far as set forth in the appended claims.

What is claimed is:

1. A combination bill and key case comprising outer and inner long layers attached together to form a long side-opening or bill-fold pocket and foldable as a whole in three sections, and key holding means mounted on one of said sections at the exterior side of the inner of said layers, and the middle section of the inner layer having a flap adapted to fold out and down to close the long pocket, and means for fastening such flap, whereby said pocket with the bills therein will surround and enclose the keys on said key holding means, while said flap closes the open side of the long pocket.

2. A combination bill and key case comprising outer and inner long layers attached together to form a long side-opening or bill-fold pocket and foldable as a whole in a plurality of sections, and key holding means mounted on one of said sections at the exterior side of the inner of said layers, whereby said pocket with the bills therein will surround and enclose the keys on said key holding means, the outer layer at its middle section having a flat supplemental pocket, and the inner layer at its middle section having a flap adapted to fold out and down to close both the long pocket and supplemental pocket, and fastening means for such flap.

In testimony whereof, I have affixed my signature hereto.

LEOPOLD G. STANLEY.
